CLAIM

The ornamental design for a horse stirrup, as shown and described.

DESCRIPTION

FIG. 1 is a front view of a horse stirrup, according to the present invention.

FIG. 2 is a top plan view of the horse stirrup of FIG. 1.

FIG. 3 is a bottom plan view of the horse stirrup of FIG. 1.

FIG. 4 is a left side view of the horse stirrup of FIG. 1.

FIG. 5 is a right side view of the horse stirrup of FIG. 1.

FIG. 6 is a perspective view of the horse stirrup of FIG. 1; and,

FIG. 7 is an open position front view of the horse stirrup of FIG. 1, in which the adjustable coiled spring portion is shown bent in a direction.
